Primary Examiner — Jennifer Rivard

(57) **CLAIM**

I claim the ornamental design for a depilatory apparatus, as shown and described.

DESCRIPTION

1.1: perspective view of the depilatory apparatus;
1.2: front view thereof;
1.3: back view thereof;
1.4: left view thereof;
1.5: right view thereof;
1.6: top view thereof;
1.7: bottom view thereof;
1.8: perspective view thereof;
1.9: perspective view of the depilatory apparatus without the flash window;
1.10: front view thereof;
1.11: back view thereof;
1.12: left view thereof;
1.13: right view thereof;
1.14: top view thereof;
1.15: bottom view thereof;
1.16: perspective thereof;
1.17: perspective view of the flash window;
1.18: front view thereof;
1.19: back view thereof;
1.20: left view thereof;
1.21: right view thereof;
1.22: top view thereof;
1.23: bottom view thereof; and
1.24: perspective view thereof.

The flash window and the depilatory apparatus without the flash window are both shown separately for convenience of illustration.

1 Claim, 24 Drawing Sheets
